CLAIM

The ornamental design for a display screen with an augmented reality overlay of a graphical user interface, as shown and described.

DESCRIPTION

FIG. 1 is a front view of a display screen with an augmented reality overlay of a graphical user interface showing a first embodiment of the new design; and,

FIG. 2 is a front view of a display screen with an augmented reality overlay of a graphical user interface showing a second embodiment of the new design.

The outer broken-line rectangle shows the perimeter of a display screen and forms no part of the claimed design. All other broken lines showing portions of the graphical user interface depict portions of the article and form no part of the claimed design.

1 Claim, 2 Drawing Sheets
